UNITED STATES PATENT OFFICE

JOHN C. STOKES, OF HOUSTON, TEXAS, ASSIGNOR TO REED ROLLER BIT COMPANY, OF
HOUSTON, TEXAS, A CORPORATION OF TEXAS

ROLLER BIT

Original application filed August 23, 1927, Serial No. 214,826. Divided and this application filed
January 26, 1928. Serial No. 249,528.

This invention relates to deep well drilling apparatus, and more particularly to roller bits of the type disclosed in my application for Letters Patent of the United States, filed 5 August 23rd, 1927, Serial No. 214,826, of which this application is a division.

The invention has for its object the provision of a roller bit embodying means, independent of its roller cutters, to effect cleaning 10 of its roller cutters without practical interference with the free revolution thereof.

Other objects will hereinafter appear.

The preferred embodiments of the invention are illustrated in the accompanying 15 drawings, in which Fig. 1 is a fragmentary sectional side elevation of a roller bit with the roller cutters and cleaning devices mounted therein; Fig. 2 is a detail end elevation of the mounting taken on the line 2—2 of Fig. 1; Fig. 3 is a detail end elevation of the mounting illustrated in Fig. 4, which is a side elevation partly in section.

Referring specifically to the Figs. 1 and 2 of the drawings, the bit head is indicated at 25 1, and has depending side bearing projections 1—a to support the cross roller cutter pin 2. Upon pin 2 is a sleeve 3 having integral eccentric portions 3—a and 3—b to support respectively disc-like plates 4 and 30 roller cutters 5. Sectional bushings 6 are interposed between plates 4 and portions 3—a, and sectional bushings 7 are interposed between cutters 5 and portions 3—b. It will be observed that the inside diameter of the 35 cutters 5 and the plates 4 is sufficient to permit them to be slipped over the eccentric portions 3—a and 3—b; and the bushings 6 and 7 are made sectional in order that they may 40 be placed about the eccentric portions 3—a and 3—b, respectively.

The plates 4 are freely revoluble, and revolution thereof may be effected by the cutters 5. The eccentric revolution of the cutters 45 and plates is attended by movement of the lateral surface of each cutter with respect to the lateral surfaces of adjacent plates. The material adhering to the cutters is scraped off by such movement, and as the 50 plates and cutters revolve in the same direc-

tion no practical resistance is offered to the free revolution of the latter.

It will also be noted that the lowermost edges of the cutters 5 project below plates 4, so that the cutting action of the teeth of said 55 cutters will not be interfered with.

The cutters and plates may be mounted upon the sleeve or bushing 3 by the skilled workmen at the manufacturing plant, and the driller in the field need only insert the 60 assembled cutters and plates in the recess provided therefor in the bit head, and insert pin 2 in the head and through sleeve 3. Exposure to dirt or other foreign matter of the bearing surfaces of the parts is, therefore, 65 unnecessary.

This invention provides means whereby groups of cutters and cleaning devices may be quickly and easily inserted and removed as 70 units.

Figs. 3 and 4 are illustrative of an assembly embodying a pin 8, cutters 9, and disc-like plates 10, said cutters being mounted upon said pin, and said plates being mounted upon eccentric bushings 11, bushings 11 being held 75 in place on pin 8 by suitable keys 12.

The relative disposition and revolution of the cutters 9 and 10 of Figs. 3 and 4 are the same as the relative disposition and revolution of the cutters 5 and plates 4, shown in 80 Figs. 1 and 2.

The invention is not limited to the specific 85 embodiments above described, and various changes may be made without departure from the scope of the following claims.

I claim:

1. In a roller bit, a head having a cutter recess, a plurality of disc shaped roller cutters, a plurality of disc shaped cleaning devices, and a support mounted in said recess and having a plurality of eccentric portions, and sectional bushings for said portions, said cutters and cleaning devices being so mountable on said bushings that said cleaning devices are adjacent and eccentrically rotatable 90 with respect to said cutters.

2. In a drill, a plurality of disk shaped roller cutters, a plurality of disk shaped cleaning devices, and a one piece support having a plurality of eccentric portions, and sec- 100

tional bushings for said portions, said cutters and cleaning devices being so mountable on said bushings that said cleaning devices are adjacent and eccentrically rotatable with respect to said cutters, and said cleaning devices are rotatable on one common axis and said cutters are rotatable on another common axis.

3. In a roller bit, a head having a cutter recess, a plurality of disk shaped roller cutters, a plurality of disk shaped cleaning devices, and a support mounted in said recess and having a plurality of eccentric portions, and sectional bushings for said portions, said cutters and cleaning devices being so mountable on said bushings that said cleaning devices and said cutters are adjacent each other, said cleaning devices are rotatable on one common axis, and said cutters are rotatable on another common axis below the axis of rotation of said cleaning devices.

In testimony whereof, I hereunto affix my signature.

JOHN C. STOKES.
